UNITED STATES PATENT OFFICE

HORACE H. RAYMOND, OF KENSINGTON, CONNECTICUT

MAGNETIC HANDLING APPARATUS

Application filed July 6, 1925. Serial No. 41,724.

The object of my invention is to provide practical and reliable apparatus for sorting or arranging in order articles having heads, such for instance, as nails, screws, etc. Such apparatus is used for feeding articles to packaging machines, nailing machines, assembling machines, plating machines, coating machines, and in fact any machine in which the article is to be used or treated.

10 In its preferred form, the apparatus comprises a rotating drum adapted to receive a mass or quantity of the articles to be arranged, which drum is provided with a series of electro-magnets for sequentially extricating the articles and depositing them in a guide so that they pass from the machine in question to whatever point they may be desired.

15 In the accompanying three sheets of drawings, I have illustrated one form of construction embodying the improvements of my invention.

Fig. 1 is a perspective view of a machine viewed from the entrance or hopper side.

20 Fig. 2 is a vertical sectional view and side elevation of the same.

Fig. 3 is a fragmentary sectional view of one of the electro-magnets.

Fig. 4 is a rear view, parts being broken away to show details of construction.

25 Figs. 5 and 6 are details of the electric commutator.

The drum 10 is provided with a hub 11 supported by the standard 12, having the bearing 13. This hub may be conveniently secured in position by a bolt 14 which passes through an external disc 15 and screws into an interior disc 16.

30 The drum is preferably mounted to rotate on a horizontal axis and is provided with a recess or chamber 17 for the articles which are to be separated and arranged in order. At one side of the drum I mount a hopper 18 so that a substantial quantity of the articles may be handled at one charge of the machine. The standard 12 and hopper 18 may be conveniently supported on a base 19 and a post 20 or in any other suitable manner.

35 The drum 10 is preferably provided with a flange constituting the walls of said recess,

a peripheral flange 21 and an outer flange 22 which may conveniently serve as a belt surface for driving the drum. The parts are so constructed as to provide a chamber 23 for a series of electro-magnets 24. Each magnet 55 consists of a coil wound on a sleeve 25 and provided with a core 26 of magnetic material. This core is provided with an inner head 27 which is preferably elongated circumferentially with respect to the drum. The back 50 of the recess 23 is open to permit the magnet coils to be inserted, and the drum is provided with passages for the cores 26 of the magnets. Each magnet is held in place by a screw 28 which screws into the outer end of 65 its core and thus clamps the magnet to the drum. The outer periphery of the drum may be provided with openings for the screws 28 and screw caps 29 for closing the openings. The recess 23 is preferably closed by a cover 70 plate 30 held in place in any suitable manner. The drum is preferably formed of non-magnetic material and may be of a single aluminum casting. The recess 17 is preferably provided with a brass liner 31 through which the 75 heads or pole pieces 27 of the magnets project.

The insulating ring 32 is mounted on the standard 12 adjacent the rear wall of the drum 10 and secured in position by one or 80 more screws such as 33. The screw 33 passes through an elongated slot 34 in the standard so that the ring 32 may be circumferentially adjusted for the purpose hereinafter described. This insulating ring 32 may be of 85 what is commonly termed "fibre" and carries two commutators, 35 and 36. The commutator 35 is in the form of a continuous ring, whereas the commutator 36 is in the form of a segment which extends from a point below 90 the axis of the drum to a point which is above the axis, that is, it is substantially semi-annular. These commutators may be secured to the insulating supporting ring 32 in any suitable manner and are provided with terminals 37 and 38, respectively, for the cable which provides the electric current. Each magnet coil is connected to the brush 40 which engages the outer ring 35 and each coil has an individual brush 41 engaging the 103

inner commutator segment 36. It will thus be seen that each magnet will be energized during that portion of each revolution in which its brush 41 engages the commutator segment 36. Preferably the brushes and commutators are protected by a cover 42 which is secured to the back of the drum and a shield 43 which is secured to the standard 12.

13 The discharge guide preferably consists of two members 44 spaced apart from each other a sufficient distance to permit the passage of the shank of the articles to be sorted, or arranged, and the upper end of the guide 15 is arranged spaced apart from the upper wall of the recess 17 in the drum a sufficient distance to allow for the passage of the head of the article. The inner end of the space between the guide members is arranged in the 17 plane of the centers of the pole pieces 27. 19 The width of these pole pieces is preferably narrow as indicated on the drawing. The current strength is such as to make the magnets only pick up articles and carry them 23 around in the plane of the opening between the inner end of the guides. Of course when an object is picked up by its end as is illustrated in Fig. 4 of the drawing, the object is supported above its center of gravity. By 25 having these pole pieces comparatively small the effect of the magnets is concentrated and the likelihood of picking articles up by their small ends is minimized. Of course if an article is picked up by the small end, no particular harm is done as it would, of course, 30 drop through the guide when released by the magnet, but it is desirable that the articles should be picked up properly, otherwise a number of articles may be picked up and then 35 uselessly dropped without being properly deposited in the deflecting guide. The shape and size of the guide 44 will of course depend upon the shape and size of the articles to be handled.

40 45 The commutator segment 36 is preferably so arranged or adjusted as to cause each magnet in turn to be energized at the bottom of the hopper and de-energized just as it passes over the upper inner end of the deflecting guide. This not only saves useless expenditure of energy but insures the rapid pick-up and deposit of the articles in the guide as the drum is rotated. The guide is so constructed and arranged, however, as to tend to properly deflect and detach the articles from the drum, even in case the magnet retains some of its attractive power.

50 55 The hopper is preferably provided with an inner flange 45 which extends into the drum recess and covers the heads of the magnets throughout a part of the circumference of the drum. This keeps the weight of the mass of articles off the drum except during the time necessary for the magnets to act.

60 65 A guard plate 46 is preferably provided

and may be secured to the inner wall of the guide 44 next to the edge of the rotating drum so as to prevent articles from dropping down between the drum and the guide 44. The inner end 47 projects inside the drum above the guide 44 to prevent any interference with the operation at this point. 70

The drum is also preferably provided with interior projections as 48 which serve to agitate the mass of articles within the drum as the drum rotates. Such agitation is particularly desirable when the articles being handled are large. 75

These projections 48 may be hollow and serve as convenient conduits 49 for the wires 80 (not shown) leading from the brushes to the magnets.

It is possible by apparatus of this character to automatically handle great quantities of articles at high speed at very small cost of 85 operation. The construction is very simple and inexpensive and requires a minimum amount of supervision and repair. 90

I claim:

1. A magnetic handler comprising a rotatable drum having a lateral recess and a plurality of electromagnets having their poles disposed at intervals around and outside the rim of said recess, a horizontally disposed bearing for said drum, spaced guides extending into said recess to a point adjacent the upper portion of the path of movement of said magnet poles, the inner ends of said guides being spaced apart axially of said drum and means for controlling the current 95 supplied to said magnets. 100

2. A magnetic handler comprising a rotatable drum having a lateral recess, a hopper extending laterally of said recess, a plurality of electromagnets having their poles disposed at intervals around and outside the rim of said recess, and spaced guides extending into said recess to a point adjacent the path of movement of said magnet poles immediately beneath the top of the recess in the drum 105 and spaced to engage an elongated headed object before it is released by a magnet. 110

3. A magnetic handler comprising a rotatable drum having a lateral recess and a plurality of electromagnets having their poles disposed radially at intervals around and outside the rim of said recess, spaced guides extending into said recess to a point adjacent and extending across the path of movement of said magnet poles, and means for controlling the current supplied to said magnets, said guides being shaped to engage articles depending from said poles as they move past, to retain those articles having their heads up and reject those with their heads down. 115 120

4. A magnetic handler comprising a rotatable drum having a lateral recess closed at one side and a plurality of electromagnets having their poles disposed at intervals 125 130

- around and outside the rim of said recess, guides extending into said recess to a point adjacent an upper portion of the path of movement of said magnet poles, and a hopper 5 extending from one side of said drum, the recess in said drum extending below the bottom of said hopper, and said hopper bottom extending across said recess to enable said magnets to extract articles from the side of 10 a pile on said hopper bottom in the recess.
5. A rotatable drum having a recess, a hopper supplying said recess, a series of magnets having poles exposed in said recess, and guides for headed articles extending over the 15 edge of said hopper into said recess to a point adjacent the path of movement of said poles immediately beneath the upper wall of the recess, said guides being constructed to engage such headed articles as are depending 20 from said magnet poles and retain those having their heads up, those having their heads down being rejected by said guides.
6. A magnetic handler comprising a rotatable drum having a recess and a number 25 of electro-magnets arranged around said recess, a hopper having a flange extending into said recess and forming a part of the load supporting bottom wall thereof and guides leading out of said recess, said electro-magnets co-operating with objects held by the 30 hopper to raise them for engagement with said guides.
7. A drum for a magnetic handler comprising a one-piece non-magnetic casing having 35 a central recess in the front and an annular recess in the rear and magnets mounted in said rear recess with poles extending into the front recess.
8. A magnetic handler comprising a low 40 rotatable drum open at one end and closed at the other, magnets thereon, a guide having spaced ends projecting inside said drum and a guard plate secured laterally of said guide between it and said drum.
- 45 9. A magnetic handler comprising a rotatable drum having a central recess in its face and an annular recess at its rear and a group of electro-magnets spaced circumferentially in said annular recess, the poles 50 of said magnets extending into said central recess, means for energizing said magnets throughout a part of a revolution of said drum, means for adjustably timing the energizing of said magnets, a hopper feeding 55 into said central recess, and spaced guides extending into said central recess and adapted to assist in the removal of headed articles from said magnets.
10. A handling machine consisting of two 60 shallow concentric rotatable cylinders, carrying electro-magnets between the walls of said cylinders, the cores of said magnets being radially disposed and extending through the wall of the inner cylinder, a hopper feeding 65 into one end of said inner cylinder, a plurality of contacting brushes, one for each of said magnets, a segments angularly adjustable about the centers of said cylinders adapted to energize said magnets successively throughout a portion of each revolution, and 70 spaced guides extending into the inner cylinder adapted to carry away articles clinging to said magnets.
11. A magnetic handler comprising an aluminum drum having a supporting hub at 75 one side and with an open recess at the other side and having a cylindrical flange constituting the recess walls, a series of electro-magnets secured to said flange with elongated pole pieces extending through said flange into 80 said recess, and spaced guides for headed articles having its entrance end in said recess in the path of movement of the shanks of articles held by the pole pieces above the centers of gravity of said articles. 85
12. A magnetic handler comprising a non-magnetic hollow drum provided with magnets carried outside said drum and having their pole pieces extending through the drum peripheral walls, and means for rotating said 90 drum and its magnets.
13. A magnetic handler comprising magnets, a movable support therefor having a recess about which said magnets are arranged in such manner that elongated headed objects of magnetic material may hang substantially vertically from the pole pieces during 95 upward travel of the magnets, a hopper for articles adjacent said magnets in the lower portions of their travel, means for raising 100 said magnets and guide means for withdrawing such objects from the pole pieces, the pole pieces of the magnets which cooperate with the objects being so shaped and located as to direct the objects into the guides. 105
14. In an apparatus for handling elongated headed objects, the combination with a hopper, of a carrier constructed to withdraw such objects from the hopper endwise and with the heads of said objects either up or 110 down and means spaced from the hopper for withdrawing all the objects from said carrier, said means being shaped to support only those objects having their heads adjacent 115 said means and their shanks in substantially the plane of movement of said carrier while rejecting all other objects on said carrier, said guides being shaped adjacent said carrier to reject those objects entering the guides 120 and having their heads inverted.
15. The combination with a hopper, of means for carrying elongated headed objects from said hopper while supporting said objects above their centers of gravity and with 125 their heads either up or down, and means for extracting said objects from said carrier, said extracting means being constructed to reject those objects within said means having their heads below their centers of grav- 130

ity and retaining and feeding those objects having their heads above their centers of gravity.

16. A magnetic handler comprising a hopper, movable magnetic means for carrying elongated objects of magnetic material from said hopper all in substantial parallelism, and guide means extending into the path of movement of said objects to receive and hold at least a substantial portion of them in parallelism.

17. A magnetic handler comprising a hopper, a magnet, means for moving said magnet to withdraw an elongated object of magnetic material from said hopper suspended from one end and a guide for engaging such an object suspended from one end by the magnet and for directing the movement of the object away from said magnet, the magnet being adapted to carry the object in a position for engagement with the guide.

18. A handling and selector mechanism for elongated headed objects comprising a hopper, a carrier for withdrawing such objects from the hopper, and guide means extending adjacent said carrier for receiving objects therefrom, said guide means being shaped adjacent the carrier to retain those objects having heads in one direction and reject those received objects having heads inverted.

19. A magnet handler comprising a hopper, a carrier for withdrawing objects of magnetic material from the hopper and provided with a magnet, the carrier and magnet being movable below the hopper bottom, means for having the magnet inactive during its downward movement below the level of objects within the hopper, and means for rendering said magnet effective through at least a portion of its upward travel.
